TYPOGRAPHICAL SLUG CASTING MACHINE

Christian Augustus Albrecht, Berlin, Germany,
assignor to Mergenthaler Linotype Company,
Brooklyn, N. Y., a company of New York

Application May 10, 1935, Serial No. 20,802
In Germany May 18, 1934

17 Claims. (Cl. 199—47)

The invention relates to typographical slug casting machines particularly adapted for casting from lines of matrices manually inserted into the machine. Heretofore in machines normally adapted for casting from machine-composed matrices, and wherein such matrices are transferred to a vertically movable transporter or first elevator by which they are conveyed to and from casting position, it has been proposed to 5 provide for casting from lines of hand composed matrices by using, in conjunction with means for retaining the elevator in an inactive position clear of the casting mechanism, special forms of composing sticks which can be applied to and 10 detached from a stationary member of the machine or so-called vise frame with which the elevator normally co-operates in presenting a machine composed matrix line to the mould. In more recent developments of machines of this kind designed solely for the use of hand composed matrices, it has been proposed to 15 transfer composed matrix-lines from a composing stick to the elevator, or to insert the line and composing stick as a whole into the elevator, which is arrested in an upper position 20 to receive the matrix line and subsequently operated to convey the line to and from the casting position.

The principal object of the present invention is 25 to further simplify the construction of machines designed for the reception of matrix-lines manually inserted in the machine, by dispensing with the first elevator altogether, and by providing the stationary member of the machine, or so-called vise-frame, with a matrix-line carrier or hand stick carrier permanently mounted thereon, into which matrices, or a hand stick wherein matrices have been composed in line, may be inserted directly by hand. Further features of the 30 invention consist in the provision of means adjustable to vary the level at which the composed line is supported in relation to the mould, and the provision of a safety device co-operating with a pump stop lever of known form whereby the 35 ejection of metal from the mould is prevented in the event of the machine being set into operation without a matrix line having been placed in casting relationship to the mould.

The invention is herein more particularly described with reference to the accompanying drawings, in which:—

Figure 1 is a front elevation of the pertinent parts of a machine with one constructional form 50 of the invention applied thereto;

Figure 2 is a plan view of the parts represented in Figure 1;

Figure 3 is a rear elevation of the vise frame of the machine showing a hand stick in operative position thereon;

Figure 4 is a central vertical section of the parts shown in Figure 1, with the carrier adjusting lever in its central position;

Figure 5 is a fragmentary plan view of a detail;

Figure 6 is a rear elevation, similar to Figure 3 illustrating the pump stop lever actuating device, and

Figures 7 and 8 are plan views showing the said device in respectively different positions.

The mould disc 1 is provided, in the customary manner, with a number of moulds one of which is indicated by the reference numeral 2, Figure 4. In front of the mould disc is located a relatively stationary member 3 of the machine in which the line of matrices is supported during casting; said member corresponds to the so-called vise frame of known machines and is hereinafter designated by that term. In the constructional example illustrated, it is assumed that the vise frame is, as usual, pivotally mounted in the machine frame, to which it is locked, in the operative position, by means of bolts 4, one only of which is illustrated in the drawings.

To permit the direct introduction of a composing stick into the vise frame, a composing stick carrier is provided which, in the constructional example given, comprises a stationary part 5 rigidly attached to the vise frame and an adjustable part 6. The stationary part 5 has an upper horizontal flange extending over the top of the vise frame and positioned thereon by means of screws 7, and a vertical flange extending downwardly at the rear of the vise frame to which it is secured as by screws 7a. The adjustable part 6 is vertically guided in the vertical flange of the part 5 by a dovetail tongue-and-groove connection 8. To effect adjustment of the member 6, a rack 9 is secured within a recess 9a in the said member, with which rack engages a pinion 10, also located within the recess, which is fixed to the end of a shaft 11 turning in a bearing member 12 secured either to the member 5 as shown or to the vise frame 3. The forward end of the shaft 11 has fast on it an adjusting lever 13. The free end 16 of the said lever 13 is formed hollow and fitted with a spring 14 and a plunger 15 having at its outer end a knurled cap 17 and at its inner end a pin 18 adapted to engage one or other of a number of holes 19 in a

segmental plate 20. The plate 20 may be formed integral with the bearing member 12, and may be provided with a division scale indicating the adjustments represented by the respective holes 5 19, so that by the adjustment of the lever 13 to the desired position, the pinion 10 will be turned and the rack bar 9 moved to adjust the member 6 to a higher or lower level.

The composing stick 21 in which the matrices 10 22 are composed in line, consists of a frame, the lower wall of which, in the constructional form illustrated, is angular in cross-section as shown in Figure 4. At one end of the frame there is a jaw 23 adjustable by a screw 24 to securely hold 15 the line of matrices in the frame. The frame is supported upon angle-shaped stops 26 by two ledges 25 located on its lower face.

The frame is further provided with two downwardly projecting lugs 25 which are adapted to 20 rest against stops 26 secured to the member 6, which stops are recessed to retain the lugs against displacement in a direction perpendicular to the member 6. To prevent lateral displacement of the hand stick when positioned in 25 the carrier, a lug 28 extending downwardly from the lower wall of the hand stick abuts against the side of one of the stops 26, and the opposite sidewall of the stick rests against an abutment 27. To secure the hand stick against vertical displacement a screw 29 fitted with a collar 30 is 30 provided in the member 6. As shown in Figures 2 and 5 the collar 30 is cut away, so that in one position, that illustrated in Figure 5, the hand stick 21 may be freely inserted from above into the member 6, while in another position, illustrated in Figure 2, the collar 30 engages the top of the hand stick 21 and secures it against upward movement. On the collar 30 an abutment pin 31 is provided, which, in the position shown 40 in Figure 5, bears against a shoulder 32 on the member 6. On the underside of the collar 30 there is a spiral groove 33, which, when the screw is rotated, engages over a pin 34 on the hand stick 21 and holds the latter against the 45 member 6.

The mode of operation of the device is as follows:—The matrices 22 are inserted and clamped in the hand stick 21 in known manner. With the screw 29 and collar 30 in the position shown 50 in Figure 5, the hand stick is placed against the member 6, and the screw 29 gives a quarter turn. The hand stick is then securely held between the abutments 26 and 27 and the collar 30. The lever 13 is then adjusted according to the level at 55 which it is desired to align the matrices relatively to the mould slot, and locked in its adjusted position by the engagement of the pin 18 in the appropriate hole 19. The casting operation then follows in the usual manner; after casting, the hand stick is removed from the machine 60 and may be replaced by another hand stick.

The constructional form of hand stick carrier above described is intended for application to a vise frame which conforms as nearly as possible 65 to standard construction, but devoid of the usual vise jaws one of which normally serves, on correct justification of a machine composed matrix line, to control a safety device by which the casting pump is permitted to act. In the use of a hand stick as above described, it may happen 70 that the machine is inadvertently started without a hand stick having been inserted, or with an empty hand stick in position on the carrier, and it is desirable that in such circumstances

the pump safety device should become operative to prevent ejection of metal from the metal pot. The arrangement illustrated in Figures 6 to 8 has been provided for this purpose. According to the said arrangement, a plunger 35 5 mounted in the carrier member 6, is urged outwardly towards the line of matrices in the hand stick, by a spring 36. The plunger 35 is formed with a recess 35a having one inclined wall, with which recess the bevelled end of a plunger 37 is 10 adapted to engage under the influence of a spring 38. The opposite end of the plunger 37 bears against a U-shaped slide 39 the outer arm of which contacts with an adjustable abutment 41 on a pump stop lever 40 of known form. 15 Normally the plunger 35 occupies the position indicated in Figure 8, and the pump stop lever 40, under the action of a spring not shown, is in position to prevent the actuation of the pump. When a hand stick containing a line of matrices 20 is inserted into the carrier, the plunger 35 will be pushed back to the position in which it is shown in Figure 7, and the plunger 37 will be cammed leftwardly as viewed in that figure so that, through the slide 39, the pump stop lever 40 will be moved to its inactive position, and the casting operation permitted to proceed, which operation, however, cannot occur in the absence of matrices 25 to depress the plunger 35.

It will be understood that the foregoing description deals with a preferred form of the invention, and that modifications or variations of the constructions exemplified may be made without departing from the invention. For example, 30 the adjustable member 6 of the carrier for receiving the hand stick 21 might be dispensed with, and the hand stick itself provided with suitable devices such as set screws or other adjustable stops to support the stick on the carrier 35 at the desired level.

Moreover, although the use of a hand stick as above described has the advantage that a number of composing sticks can be made available for the composition of fresh lines whilst 45 those previously composed are being cast, the composing stick could be arranged to form part of the member hereinbefore termed the carrier; in that case, by tilting back the vise frame, the matrices could be inserted directly into the 50 carrier.

Having described my invention, I declare that what I claim and desire to secure by Letters Patent is:—

1. In a typographical slug casting machine, 55 the combination with a mould and a stationary vise frame, in which a line of matrices is supported in casting relation to the mould, of a hand stick in which matrices are composed in line, a hand stick carrier permanently mounted on the vise frame, comprising a member slidable in fixed guides, a rack operatively fast to said slidable member, a pinion engaging said rack, a bearing member fixed relatively to the vise frame in which said pinion is rotatable, a 60 lever adapted to rotate said pinion and a locking device adapted to secure said lever against displacement from its adjusted position.

2. In a typographical slug casting machine, the combination with a mould and a stationary vise 70 frame in which a line of matrices is supported in casting relation to the mould, of a hand stick in which matrices are composed in line, a hand stick carrier permanently mounted on the vise frame, co-operating lugs and abutments on the 75

hand stick and carrier adapted to determine the position of the stick relatively to the carrier, and a locking device operable to secure the hand stick in said determined position.

5. In a typographical slug casting machine, the combination with a mould and a stationary vise frame in which a line of matrices is supported in casting relation to the mould, of a hand stick in which matrices are composed in line, a hand stick carrier permanently mounted on the vise frame, co-operating lugs and abutments on the hand stick and carrier adapted to determine the position of the stick relatively to the carrier, and a mutilated collar rotatably mounted on the carrier adapted in one position to permit free insertion and removal of the hand stick and in another position to overlie the stick and lock it on the carrier.

4. In a typographical slug casting machine, a combination according to claim 3, characterized by a spiral groove on the underside of the locking collar, and a pin on the carrier engaged by said groove when the collar is turned to active position, to hold the hand stick against the carrier.

5. In a typographical slug casting machine, the combination with a mould and a stationary vise frame in which a line of matrices is supported in casting relation to the mould, of a hand stick in which matrices are composed in line, a hand stick carrier permanently mounted on the vise frame, co-operating lugs and abutments on the hand stick and carrier adapted to determine the position of the stick relatively to the carrier, a mutilated collar rotatably mounted on the carrier adapted in one position to permit free insertion and removal of the hand stick and in another position to overlie the stick and lock it on the carrier, and means secured to the vise frame operable to adjust the level at which the hand stick is supported relatively to the mould.

6. In a typographical slug casting machine, the combination with a mould, a stationary vise frame, a pump stop lever and a hand stick adapted to be inserted into the stationary vise frame to support a composed line of matrices in casting relation to the mould, of a pump stop lever control device actuated to release the pump by the insertion into the vise frame of the hand stick with its composed line of matrices.

7. In a typographical slug casting machine, the combination with a mould, a stationary vise frame, a pump stop lever and a hand stick adapted to be inserted into the stationary vise frame to support a composed line of matrices in casting relation to the mould, of a spring-loaded plunger normally extending beyond the vise frame in a position to be depressed by a line of matrices inserted into said vise frame, and connections between said plunger and the pump stop lever whereby the latter is actuated to release the pump when the plunger is depressed.

8. In a typographical slug casting machine, the combination with a mould, a stationary vise frame, a hand stick carrier mounted on the vise frame, a hand stick adapted to be inserted into said carrier to support a composed line of matrices in casting relation to the mould, and a pump stop lever, of a spring-loaded plunger mounted in the carrier and extending therefrom in a position to be depressed by a line of matrices when the hand stick is positioned on the carrier, a second spring loaded plunger mounted in the carrier of the first-named plunger to move the pump stop lever to pump-releasing position.

9. In a typographical slug casting machine, the combination with a mould, a stationary vise frame, a hand stick carrier mounted on the vise frame, a hand stick adapted to be inserted into said carrier to support a composed line of matrices in casting relation to the mould, and a pump stop lever, of a spring-loaded plunger mounted in the carrier and extending therefrom in a position to be depressed by a line of matrices when the hand stick is positioned on the carrier, a second spring-loaded plunger mounted on the carrier normally engaged with a recess in the first-named plunger and adapted to be moved out of the recess when said first-named plunger is depressed, and a slide actuated by said movement of the second plunger to move the pump stop lever to pump-releasing position.

10. In a typographical slug casting machine, the combination with a mould and a stationary vise frame in which a line of matrices is supported in casting relation to the mould, of a hand stick wherein matrices are composed in line, and a hand stick carrier permanently mounted on the vise frame and having a fixed portion whereon is mounted a vertically adjustable section adapted to receive a hand stick manually inserted therein.

11. A combination according to claim 10, including manually operable means mounted on the carrier for adjusting the adjustable section which receives the hand stick.

12. In a typographical slug casting machine, the combination with a mould and a stationary member of the machine in which a line of matrices is supported in casting relation to the mould, of a matrix-line carrier permanently mounted on said stationary member, said carrier comprising a fixed part and an adjustable part slidably mounted thereon, the adjustable part being adapted to receive and support a composed matrix line manually inserted in the machine.

13. In a typographical slug casting machine, the combination with a mould and a stationary member of the machine in which a line of matrices is supported in casting relation to the mould, of a matrix-line carrier permanently mounted on said stationary member, said carrier comprising a fixed part and an adjustable part slidably mounted thereon, the adjustable part being adapted to receive and support a composed matrix line manually inserted in the machine and being adjustable vertically to vary the level at which the matrix line is supported relatively to the mould.

14. In a typographical slug casting machine, the combination with a mould and a stationary vise frame in which a line of matrices is supported in casting relation to the mould, of a hand stick wherein matrices are composed in line and a hand stick carrier permanently mounted on the vise frame, said carrier comprising a fixed part and an adjustable part slidably mounted thereon, the adjustable part being equipped with means to receive and support the hand stick when manually inserted in the machine.

15. In a typographical slug casting machine, the combination with a mould and a stationary vise frame in which a line of matrices is supported in casting relation to the mould, of a hand stick wherein matrices are composed in line and a hand stick carrier permanently mounted on the vise frame, said carrier comprising a fixed part and an adjustable part slidably mounted thereon, the adjustable part being equipped with means to receive and support the hand stick when manually inserted in the machine and being adjust-

able vertically to vary the level at which the hand stick is supported relatively to the mould.

16. In a typographical slug casting machine, the combination with a mould and a stationary vise frame in which a line of matrices is supported in casting relation to the mould, of a hand stick wherein matrices are composed in line and a hand stick carrier permanently mounted on the vise frame, said carrier comprising a fixed part and an adjustable part slidably mounted thereon, the adjustable part being equipped with means to receive and support the hand stick when manually inserted in the machine and the fixed part being equipped with means for actuating the adjustable part to vary the level at which the hand stick is supported relatively to the mould.

17. In a typographical slug casting machine, the combination with a mould and a stationary vise frame in which a line of matrices is supported in casting relation to the mould, of a hand stick wherein matrices are composed in line and a hand stick carrier permanently mounted on the vise frame, said carrier comprising a fixed part and an adjustable part slidably mounted thereon, cooperating means on the adjustable part and the hand stick to prevent displacement of the stick relatively thereto, and means for actuating the adjustable part to vary the level at which the hand stick is supported relatively to the mould.

15

CHRISTIAN AUGUSTUS ALBRECHT.
